CLAIM

The ornamental design for a floating drink holder as shown and described.

DESCRIPTION

FIG. 1 is a perspective view of a floating drink holder showing the new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The even-length broken lines in the figures represent portions of the floating drink holder that form no part of the claimed design.

The cord of the float drink holder is shown with a symbolic break in its length in FIGS. 1, 2, 6 and 7. The break lines and appearance of any portion between the break lines form no part of the claimed design.
